UNITED STATES PATENT OFFICE.

ZENE MAULSBY, OF EVERETT, WASHINGTON.

DESIGN FOR A BURIAL CASKET.

Application filed February 24, 1925. Serial No. 12,464. Term of patent 3½ years.

To all whom it may concern:

Be it known that I, ZENE MAULSBY, a citizen of the United States, residing at Everett, in the county of Snohomish, State of Washington, have invented a new, original, and ornamental Design for a Burial Casket, of which the following is a specification, reference being had to the accompanying drawing, forming part thereof.

The drawing is a perspective view of the burial casket, with a section of the top in open position, showing my new design.

I claim:

The ornamental design for a burial casket, as shown.

ZENE MAULSBY.
